SWIMMING POOL OR THE LIKE

Joseph Diemond, Simsbury, and Melvin Y. Gershman,
West Hartford, Conn., and Henry L. Sundberg, Jr., and
Norbert A. Vangsness, Longmeadow, Mass., assignors
to Coleco Industries, Inc., Hartford, Conn., a corpora-
tion of Connecticut

Filed Jan. 5, 1966, Ser. No. 484

Term of patent 14 years

(Cl. D13—1)

FIG. 1

FIG. 2

FIG. 3

FIG. 4

FIG. 5

FIG. 6

FIG. 7

FIG. 8

FIG. 9

FIG. 10

FIG. 11

FIG. 12

FIGURE 1 is a perspective view of a swimming pool or the like, showing our new design;

FIGURE 2 is a plan view thereof;

FIGURE 3 is a side elevational view thereof, the other side being substantially identical;

FIGURE 4 is an end elevational view thereof;

FIGURE 5 is a perspective view of another swimming pool embodying our new design;

FIGURE 6 is a plan view thereof;

FIGURE 7 is a side elevational view thereof, the other side being substantially identical;

FIGURE 8 is an end elevational view thereof;

FIGURE 9 is a perspective view of still another swimming pool embodying our new design;

FIGURE 10 is an end elevational view thereof;

FIGURE 11 is a perspective view of a further swimming pool embodying our new design; and

FIGURE 12 is an end elevational view thereof.

The dominant features of the design reside in the portions shown in full lines.

We claim:

The ornamental design for a swimming pool or the like, as shown and described.
